Gilbert L. Sheldon

UNITED STATES PATENT OFFICE.

GILBERT L. SHELDON, OF NEW MARLBOROUGH, MASSACHUSETTS.

IMPROVEMENT IN TRUCKS FOR PULLING STONE.

Specification forming part of Letters Patent No. 39,838, dated September 8, 1863; antedated July 26, 1863.

To all whom it may concern:

Be it known that I, GILBERT L. SHELDON, of New Marlborough, in the county of Berkshire and State of Massachusetts, have invented a new and useful Improvement in Trucks for Pulling and Lifting Stones; and I do hereby declare that the following is a full, clear, and exact description of the same, reference being had to the accompanying drawing, making a part of this specification, in which the figure is a perspective view of my invention, showing the truck in the act of pulling a stone.

The nature and peculiar characteristics of my invention will be readily understood from the drawing.

A is a pulley, mounted, as represented, on a shaft upon the frame K K K K K K, which latter is attached to the single cross piece H. The pulley A is operated by means of the rope or chain D passing through the small pulley shown, and to which the team is attached, as shown in the figure.

B is a chain, both ends of which are attached to the shaft of the pulley A, one end on each side of the said pulley, in such a manner as to equalize the strain on the pulley-shaft. The chain B is made fast below to the stone F, which is retained in position as it is being pulled or lifted by means of the ratchet

and pawl a'. After the stone is sufficiently pulled or lifted, the team is then attached to the truck and the stone is conveyed from the field.

The merits of my invention are as follows: Simplicity and cheapness of construction and operation, also effectiveness and durability—the purchase obtained being very considerable, and the strain or wear and tear on the truck being for the most part in direct line with its greatest strength.

What I claim as my invention, and desire to secure by Letters Patent of the United States, is—

1. The combination on the single bar H of the frame K K K K K K and single pulley A with its accompanying shaft and ratchet a', substantially in the manner and for the purposes described.

2. The use of the chain B, in combination with the single pulley A, when said chain is attached on each side of the said pulley, substantially as represented, and for the purpose described.

GILBERT L. SHELDON.
